UNITED STATES PATENT OFFICE

GEORGE KRASNEY, OF CHICAGO, ILLINOIS

COLLAR BUTTON

Application filed May 26, 1930. Serial No. 455,762.

This invention relates to new and useful improvements in collar buttons and has for its primary object to provide, in a manner as hereinafter set forth, a device of this character embodying a novel construction and arrangement of parts whereby the accidental loss of the same from the buttonhole in a shirt band will be prevented.

Other objects of the invention are to provide a collar button of the character described which will be comparatively simple in construction, strong, durable, efficient in its use and which may be manufactured at low cost.

All of the foregoing and still further objects and advantages of the invention may become apparent from a study of the following specification, taken in connection with the accompanying drawings wherein like characters of reference designate corresponding parts throughout the several views, and wherein:—

Figure 1 is a view in front elevation of a collar button constructed in accordance with this invention.

Figure 2 is a view in side elevation thereof. Figure 3 is a fragmentary view in vertical section taken substantially on the line 3—3 of Figure 1 looking in the direction indicated by the arrows.

Referring to the drawings in detail, it will be seen that the reference numeral 1 designates a flat plate of any suitable material having a curved upper end. A shank 2 is rigidly mounted on the lower portion of the plate 1 and projects forwardly therefrom and has mounted on its free end a head 3 of suitable configuration.

The plate 1 is further provided in its forward face and above the shank 2, with a recess or socket 4 into which extends an annular flange 5 for retaining a membrane 6 in position in said recess in spaced opposed relation to the bottom wall of said recess as illustrated to advantage in Figure 3 of the drawings. The membrane 6 has formed in its upper portion an opening 7 on the opposite sides of which are formed the outwardly pressed ribs 8 which provide depressions or channels on the inner side of said membrane 6 for rotatably receiving the opposite

end portion of a pintle 9 which supports an angular bar 10 which extends outwardly and then downwardly therefrom and has formed integrally on its free end a yoke 11 adapted to swing over the head 3 and straddle the shank 2.

As illustrated to advantage in Figure 3 of the drawings, the pintle 9 is oval in cross section and has a camming action against the bottom wall of the recess 4 in a manner to cause flexing of the membrane 6 upon swinging movement of the arm 10 to impart to said arm a snap action to retain the same in its operative position.

In use, the head 3 and the shank 2 are inserted in the bottom hole in the underlying end portion of the neck band with the plate 1 projecting slightly above said neck band in the manner best illustrated in Figure 2 of the drawings. The yoke 11 is then swung downwardly into engagement with the outside of the neck band and said band is thus embraced between the yoke and the plate 1. The overlapping portion of the neck band is then secured on the shank 2 and is disposed over the yoke 11 in a manner to conceal the same. It will thus be seen that I have provided a front collar button which will be retained in position in the neck band regardless of the size of the buttonhole or the extent to which the same may be worn.

It is believed that the many advantages of a collar button constructed in accordance with this invention will be readily understood, and although the preferred embodiment of the invention is as illustrated and described, it is to be understood that changes in the details of construction may be had which will fall within the scope of the invention as claimed.

What is claimed is:—

A collar button of the character described comprising a substantially flat plate having a recess in one end portion, a membrane mounted in the recess in spaced opposed relation to the bottom wall thereof, a retaining flange extending into the recess for securing the membrane therein, a pintle of substantially oval cross section mounted for rotary movement on the inner side of the membrane

and engageable with the bottom wall of the recess, an angular arm projecting outwardly from the pintle, a yoke depending from the arm, and a headed shank projecting from the plate below the recess and extending through
5 the yoke.

In testimony whereof I affix my signature.
GEORGE KRASNEY.
